ANTITURNING BOBBIN FOR AUTOMATIC LOOMS

Richard G. Turner, Worcester, Mass., assignor to Crompton & Knowles Loom Works, Worcester, Mass., a corporation of Massachusetts

Application March 3, 1938, Serial No. 193,748

7 Claims. (Cl. 242—120)

This invention relates to improvements in bobbins for automatic weft replenishing looms and more particularly to bobbins on which is wound a flat or oval package of weft, and also to the method of making such a bobbin.

In my co-pending application Serial No. 129,245, now U. S. Patent 2,128,974, I have shown a magazine for supplying reserve bobbins the horizontal transverse barrel diameter of which is greater than the vertical dimension. It is necessary that such bobbins be held in the shuttle so that they will not turn on their longitudinal axis. I have found that a bobbin of this type provided with the ordinary circular ring has a tendency to rotate in the shuttle with the result that the major transverse axis of the weft becomes oblique and projects below the bottom of the shuttle.

Shuttles used on automatic looms ordinarily have a two-jaw spring holder notched to receive the rings of the bobbin. There are ribs on the inner vertical surfaces of the spring jaws located between the notches. It is an important object of my present invention to provide the bobbin with projections located between the rings to engage the ribs of the spring jaws and thereby resist rotation of the bobbin in the shuttle.

It is a further object of my present invention to extend a holding pin transversely through the bobbin head to project beyond opposite sides of the latter sufficiently to engage the spring jaw ribs and to hold this pin in place by a ring on the bobbin head. Changing conditions of the atmosphere and drying of the wood of the bobbin are likely to loosen the pin and for this reason I make provision for holding the pin in proper position.

It is a more particular object of my present invention to taper the ends of the holding pin and locate the same so that one of the bobbin head rings engages the tapered surfaces to lock the pin in position.

It is a further object of my invention to provide an improved method for assembling the rings and pin so that these parts necessarily have cooperating engagement with each other.

With these and other objects in view which will appear as the description proceeds, my invention resides in the combination and arrangement of parts hereinafter described and set forth.

In the accompanying drawing, wherein two forms of my invention are set forth,

Fig. 1 is a top plan view of a shuttle carrying a bobbin made according to the preferred form of my present invention,

Fig. 2 is an enlarged plan view of the butt

end of the bobbin with the rings and portion of the wood shown in section.

Fig. 3 is a vertical section on line 3—3 of Fig. 2,

Fig. 4 is a detail view showing the pin and the relation which it sustains to the ring which holds it in place,

Fig. 5 shows the bobbin shuttle and transfer mechanism in position these parts sustain at the beginning of the transferring operation,

Figs. 6, 7 and 8 are diagrammatic views showing the method of assembling the rings and holding pin, and

Fig. 9 is a view similar to Fig. 3 but showing a modified form with two pins.

The shuttle S has the usual bobbin compartment 10 to receive a bobbin B, the barrel 11 of which may be non-circular preferably in the form of an oval or oblong with the major dimension horizontal when the shuttle is weaving. The shuttle is provided with a spring clip 12 having front and back jaws 13 and 14, respectively, which have a plurality of vertical notches 15 spaced by ribs 16.

The bobbin B has a head or butt 20 substantially of usual form and provided with outer and inner wire rings 21 and 22, respectively, between which is located an intermediate similar ring 23. These rings are made of hardened wire and are received by grooves 24 in the bobbin head. The rings enter the grooves 15 corresponding thereto and it is in this way that the bobbin is yieldingly held in the shuttle.

The matter thus far described, except as modified by the following description, may be of the usual construction.

In carrying my invention into effect I provide a pin 30 having a cylindrical intermediate portion 31 with its ends tapered as at 32. The length of the pin is sufficient to project beyond the periphery of the head as suggested in Fig. 3. The pin is located in a bore 33 extending transversely through the head and as indicated in Fig. 3 located above the winding spindle bore 34. The location of the bore 33 is an important part of my present invention, and as shown in Fig. 4 is positioned so that one edge 35 thereof if projected would clear the intermediate rings, but the other edge 36 if projected would extend into the outer groove 24 which receives the outermost ring 21. The pin may be formed of hardened wire and the conical ends formed in any desired manner.

When assembling the rings and pin rings 22 and 23 will be slipped into position over a conical 55

guide not as is customary to enter the inner and intermediate grooves 24, respectively, as indicated in Fig. 6. The pin 30 is then inserted through the bore 33 with its ends projecting approximately the same amount in the opposite ends of said bore, as shown in Fig. 7. The outermost ring 21 is then placed into its groove to establish holding relation with the tapered ends of the pin to prevent longitudinal movement of the latter along its axis relatively to the bobbin head, as suggested in Fig. 8. The bobbin is then ready for use in a weft replenishing mechanism designed to hold the bobbin with the pin horizontal during transfer, or at least to present the bobbin for transfer in such a position that at the end of the transferring stroke the pin will be horizontal. As shown in Fig. 3 the pin is substantially parallel to the major transverse diameter of the barrel 11.

The rings have their ends spaced slightly from each other as suggested in Fig. 1. In that figure I have shown a gap 40 between the ends of each ring, and I have shown the gaps longitudinally aligned, but this is not essential. It is apparent, however, that a bobbin made with its rings so placed gives continuous uninterrupted contact between the jaws of the shuttle spring and the bobbin rings. It is desirable, however, that the outermost ring 21 be located with its gap 40 spaced from both ends of the pin. If this were not so the pin might be able to move in one direction through the gap 40 of ring 21. I may if desired use a form of ring shown in my co-pending application Serial No. 117,704, the spring having roughened areas 50 to engage the wood of the bobbin to prevent turning of the ring on the bobbin head. By this provision the ring is held against creeping angular motion around the periphery of the bobbin and the gap 40 of the outermost ring 21 is therefore effectively prevented from moving into alignment with the pin. The latter is therefore held between parts of the outer ring 21 at all times.

During transfer the bobbin will be approximately as indicated in Fig. 5 when the transferer arm 55 is located above a bobbin support 56 which holds the bobbin in proper position for transfer. The bobbin head may be slabbed as at 57 to assist in holding the bobbin with the pin horizontal preparatory to transfer. This support is substantially parallel to the pin 30 and during downward motion of the bobbin into the shuttle S one end or the other of the pin will engage a rib 16 and will thereafter prevent further substantial downward motion of the corresponding side of the bobbin head. As transfer continues the other end of the pin will move down toward the rib 16 opposite the first rib to be engaged by the pin. During subsequent picking of the shuttle any tendency of the bobbin to turn in the shuttle jaws will be resisted by engagement between the jaw ribs and the pin. In this connection it should be noted that the pin passes through the wooden part of the bobbin so that although rings 22 and 23 may turn with respect to the bobbin, the latter will nevertheless be maintained with the major transverse barrel diameter thereof substantially horizontal.

In the modified form of the invention shown in Fig. 9 I illustrate two pins 75 each similar to the pin 30 and held by the same ring. Each pin 75 serves the same purpose as does pin 30, the use of two pins giving added assurance that the bobbin will not turn.

From the foregoing it will be seen that I have

provided a bobbin having a head from which project elements to engage the spring jaws of the shuttle to prevent rotation of the bobbin in the shuttle. It will also be seen that the pin is located at such a point along the axis of the bobbin that its tapered ends are engaged by one of the bobbin rings to prevent dislodgement of the pin. While I have shown the pin locked in position by the outermost ring, yet I do not wish to be limited to this construction, but during transfer if the shuttle is slightly misplaced toward the center of the loom a condition might arise where the outermost ring only will be held by the spring jaws. It is for this reason that I prefer to have the ring nearest the head end of the bobbin hold the pin. Furthermore, I make provision for preventing turning of the ring 21 so that a solid part thereof will engage each of the tapered ends of the pin, this provision precluding the possibility of the gap between the ends of the ring ever becoming aligned with the pin. Again, it will be seen from Fig. 5 that the support for the bobbin as it awaits transfer has a surface substantially parallel to the pin and any adjustment which may be necessary in the angular disposition of the support surface to effect proper transfer will therefore automatically locate the pin correctly.

Having described my invention it will be seen that changes and modifications may be made therein by those skilled in the art without departing from the spirit and scope of the invention and I do not wish to be limited to the details herein disclosed, but what I claim is:

1. In a bobbin, a head on one end of the bobbin, a holding ring on said head, a pin extending transversely through the head and having tapered ends projecting beyond the periphery of said head, said ring engaging the tapered ends of the pin to prevent the latter from moving transversely relatively to the head.

2. In a bobbin having a barrel the transverse horizontal diameter of which is greater than the transverse vertical diameter, a head on one end of the bobbin, a holding ring on said head, and a pin extending transversely through the head parallel to said horizontal diameter and projecting beyond the periphery of the head, said ring having holding relation with the opposite ends of the pin to prevent substantial relative transverse motion thereof with respect to the head.

3. In a bobbin having a barrel the transverse horizontal diameter of which is greater than the transverse vertical diameter, a head on one end of the bobbin, a holding ring on said head, a pin parallel to said horizontal diameter and having tapered ends extending transversely through the head, said tapered ends projecting beyond the periphery of the head and into engagement with the ring, whereby the latter prevents substantial transverse motion of the pin relatively to the head.

4. In a bobbin, a head on one end of the barrel, a holding ring located between the ends of and extending around said head and having the ends thereof separated by a gap, means to prevent rotation of the ring on the bobbin, and a pin extending transversely of the barrel and through the head and having the ends thereof in engagement with the ring at points spaced from said gap, said ring holding the pin against transverse motion relatively to the head.

5. In a bobbin, a head on one end of the barrel, a ring extending around said head and having the ends thereof separated by a gap, means

- formed on the ring to engage the head and prevent rotation of the ring on said head, and a pin having tapered ends projecting laterally beyond the periphery of the head, said ring engaging the 5 tapered ends at points spaced from said gap to prevent lateral movement of the pin in the head.
6. In a bobbin, a head formed on one end of the barrel, a pair of spaced rings on said head, said head having a transverse bore lying entirely 10 at one side of one of the rings, the other of said rings overlapping said bore, and a pin lying in said bore and having ends extending beyond the periphery of the head and into holding engagement with the second named ring, the latter pre-

venting substantial transverse movement of the pin relatively to the head.

7. In a bobbin, a head on one end of the barrel, a pair of rings on said head adjacent surfaces of which are spaced by a given distance along the 5 length of the barrel axis, said head having a bore extending transversely therethrough the axis of which lies between said surfaces and one edge of which is spaced from the surface of one of said rings by a distance greater than said given distance, and a pin in said bore having holding 10 engagement with the other ring, the ends of said pin extending beyond the periphery of the head.

RICHARD G. TURNER.
